UNITED STATES PATENT OFFICE.

DALE C. WILHELM, OF LOS ANGELES, CALIFORNIA.

DESIGN FOR AN ARTICLE OF MANUFACTURE.

46,980.

Specification for Design.

Patented Feb. 16, 1915.

Application filed May 18, 1914. Serial No. 839,450. Term of patent 7 years.

To all whom it may concern:

Be it known that I, DALE C. WILHELM, a citizen of the United States, residing at Los Angeles, in the county of Los Angeles and State of California, have invented a new, original, and ornamental Design for an Article of Manufacture, of which the following is a specification, reference being had to the accompanying drawing, forming part thereof.

The figure shows my design for an article of manufacture.

I claim:

The ornamental design for an article of manufacture, as shown.

DALE C. WILHELM.
